METHOD AND APPARATUS FOR PRODUCING
WIRE STRAND OR ROPEDartrey Lewis, Trenton, N. J., assignor to John A.
Roebling's Sons Company, Trenton, N. J., a
corporation of New Jersey

Application August 28, 1948, Serial No. 46,626

14 Claims. (Cl. 57—58.5)

1

This invention relates to a method and apparatus for producing wire strand or rope, and more particularly a wire strand or rope that has any desired amount of residual twist which may be clockwise, counter-clockwise or neutral.

It is frequently desirable to manufacture wire strand for use as such, or in the making of wire rope, which is not wild but has most or all of the "spring back" taken out of it. Sometimes a completely dead or inert strand is needed, and other times it is desirable to make a strand that has some residual twist in one direction or the other. Likewise, it is often desirable to manufacture wire rope that is dead or inert, or that has a calculated small residual twist in one direction or the other. Stranding and rope making machines heretofore used have not, to the best of my knowledge, been capable of producing satisfactorily strand or rope of such varying characteristics.

It is an object of my invention to provide apparatus and a method for producing wire strand or rope by forming the strand or rope with an overtwist and then untwisting the overtwisted product to any desired extent to obtain a product that is dead or has a residual twist in one direction or the other.

A further object of my invention is to provide such a method and apparatus in which not only the residual twist in the completed strand or rope can be controlled, but also the number of twists per inch of strand or rope can be controlled at will.

Other objects and advantages will be explained or will be apparent from the following description of the embodiments of my apparatus illustrated in the accompanying drawings, in which

Fig. 1 is an end elevation view, partly in section, of a stranding machine constructed in accordance with my invention.

Fig. 2 is a horizontal sectional view of a portion of the machine taken approximately on the line 2—2 of Fig. 1.

Fig. 3 is a side elevation view of a portion of the machine, partly in section, and taken approximately on the line 3—3 of Fig. 1.

Fig. 4 is an end elevation view, partly in section, showing a modified form of untwisting head for use in a machine constructed in accordance with my invention.

Fig. 5 is an end elevation view, partly in section, showing a modification of one part of the device of Fig. 1 to render it suitable for making a more complicated strand such as a seven wire strand, or a wire rope.

2

I have found that accurate control of the number of twists per inch, or the length of lay, as well as the final condition of the strand or rope as to residual twist can be readily accomplished by forming the wire strand or rope with a twisting head that produces a marked overtwisting of the wires or strands, and then subjecting the overtwisted strand or rope thus formed to a controlled amount of untwisting performed by a separate mechanism.

Referring more particularly to the drawings, Fig. 1 illustrates one form of my machine which may have one or more heads for making strand or rope supported by a suitable frame 10. Only one such stranding head is illustrated in Fig. 1. Mounted in the left portion of the frame as viewed in Fig. 1 are a number of reels or spools 11, three such reels being shown, each supplying an individual wire for the formation of a strand. The three wires from these reels are passed together over a freely rotating sheave or pulley 12, and thence to a pair of capstans 13, 13 mounted on parallel shafts 14, 14. The capstans 13, 13 preferably have several grooves so that the wires can be wrapped around them a number of turns to reduce slippage. Shafts 14, 14 may be positively driven by the gear 15 on the shaft 16 which in turn is driven as described below.

After passing around the last wrap on the outer capstan 13, the wires are guided through a hollow rotatable shaft 19, to a twisting head 20 formed integral with or otherwise fixed to the shaft 19.

The twisting head 20 preferably carries a pair of freely rotatable grooved rollers 21, 21 mounted on shafts 22, 22 which may or may not be inclined as shown in Fig. 3. The wires, which at this stage are twisted together into the strand, are passed a number of wraps around the grooved rollers 21, 21. The shaft 19 and twisting head 20 carrying these rollers are positively rotated about the axis of the wires or strand by a screw gear 23 driven by the screw gear 24 on shaft 24a which in turn is driven as described below. Twisting head 20 is driven at such a speed as to form a strand with an overtwist or, in other words, an amount of twist substantially exceeding that desired in the final product.

The overtwisted strand passes from the rollers 21 through a second hollow shaft 25, also mounted for rotation in suitable bearings and carrying as an integral or fixed part a flyer 26. Suitable guide pulleys 27 are mounted on the flyer 26 to guide the strand through the hollow shaft 25 and over one arm of the flyer by which the strand

is wound up on the spool 28. Hollow shaft 25 and the flyer 26 may also be rotated by a screw gear 29 driven by another screw 30 mounted on shaft 30a which in turn is driven in a manner described below. Flyer 26 is rotated in the same direction as the twisting head 20 but at a substantially lower rate of speed.

The take-up spool 28 is mounted on a shaft 31 and supported for rotation by a fleeting bar 32 of any suitable construction, as will be understood by those skilled in the art, so as to provide a reciprocating or fleeting motion to the spool 28 as the strand is wound up on it. The other end of shaft 31 preferably carries a suitable form of brake, such as the hydraulic brake 33, which may be supplied with oil or other fluid from the reservoir 34 through the flexible hose 35. A valve 36 in the flexible return line 37 from the brake to the reservoir may be used in conjunction with a suitable gauge 38 to control the amount of braking applied to the spool 28.

The various parts of the machine may all be driven from a single source of power such as the motor 18. For example, shaft 30a which is used to drive the hollow shaft 25 may be driven directly from motor 18 at a fixed speed by a chain and sprocket drive. Shaft 16, from which the capstans 13, 13 are driven, may in turn be driven from shaft 30a by a suitable variable speed drive such as sprockets of different diameters on the two shafts with a chain 17 that can be shifted from one pair to another. In this manner shaft 16 may be driven at any one of several different speeds relative to the speed of shaft 30a.

Shaft 24a, which is used to drive the hollow shaft 19, may be driven directly from motor 18 by a suitable variable speed drive, preferably one which utilizes a belt and cone or some other means to provide finely graduated variations in speed. It will be apparent that the three intermediate or drive shafts 16, 24a and 30a may be used to drive similar parts on any desired number of heads mounted side by side on the frame 10.

In the operation of this device, the wires to be formed into the strand are pulled from the reels 11 by the capstans 13, 13. Suitable brakes may be provided on the reels 11 to maintain adequate tension on the wires fed to the capstans 13 to prevent slippage on the capstans. Between the point where the wires leave the outer capstan 13 and are picked up by the rollers 21, 21 on the twisting head 20, the wires are twisted into the form of a strand, the number of twists per inch depending upon the rates of rotation at which the capstans 13, 13 and the hollow shaft 19 are driven. The hollow shaft 19 is preferably driven at a sufficiently high rate of speed to overtwist the strand in forming it.

The hollow shaft 25 carrying flyer 26 is rotated in the same direction as the twisting head 20 but at a substantially lower speed. The strand leaving the twisting head 20 is rotating on its own axis at the same speed as the speed of rotation of head 20. Thus, the strand between the rapidly rotating twisting head 20 and the first pulley 21 on the flyer 26, which is rotating at a slower speed, is untwisted by an amount proportional to the difference in speeds of rotation of these two members and to the lineal speed of the strand. The hollow shaft 25 may be driven at a fixed speed and the speeds of the capstans 13, 13 and of the hollow shaft 19 adjusted relative to it as described above, or any other suitable variable speed drives may be used to provide a

similar flexibility or adjustment of these speeds relative to each other.

The strand passing over the pulleys 21 has thus been first overtwisted in its formation and then untwisted by a controlled amount, leaving it with the desired residual tendency to twist or rotate in either direction, or completely neutral or inert, as may be wished.

The rotation of the flyer arm about the take-up spool 28 winds up the strand on the spool 28 and the hydraulic brake 33 permits some rotation of the spool 28 and maintains the desired amount of tension on the strand between the spool 28 and the capstans 13, 13. While a hydraulic brake 33 has been illustrated for this purpose, it will be apparent that magnetic or other suitable controllable brakes may be substituted therefor. As the strand passes around the first pulley 21 on the flyer 26, the strand is still rotating on its own axis but this remaining rotation is disposed of as the strand passes over the remaining two pulleys 21 on the rotating flyer arm and is wound up by it on the revolving spool 28.

Referring now to the modified form of apparatus illustrated in part in Fig. 4, this modification consists essentially of incorporating the pulling capstan in the flyer or untwisting head of the device instead of at the point shown in Fig. 1. In this modified form, the wires from the reels 11 pass over a simple sheave or through a die in place of the capstans 13, 13, thence through hollow shaft 19 and twisting head 20, as shown in Fig. 1, and from there to the untwisting head illustrated in Fig. 4.

In Fig. 4, the capstan arrangement is mounted in a suitable frame 40, which is supported for rotation on the hollow shafts 41 and 42 mounted in bearings 43 and 44. Capstans 45, 45 carried by shafts 46, 46 mounted in the frame 40 are geared together and driven by a worm and worm gear indicated generally at 47, the worm being mounted on shaft 48. One end of shaft 48 carries a gear 49 meshing with the teeth of a fixed ring gear 50 which causes the worm shaft 48 to rotate as the frame 40 is rotated about the axis of the traveling strand. Frame 40 may be rotated by suitable screw gears 51 and 52 driven from any suitable source of power (not shown). For example, gear 52 may be mounted on shaft 30a driven as described above. The journal 42 is preferably integral with or has fixed thereto a flyer 53 provided with guide pulleys 54 for delivering the finished strand to the take-up spool 55. The flyer 53 and take-up spool 55 may be mounted and operated in the same manner as the flyer 26 and take-up spool 28 shown in Fig. 1.

This modified arrangement operates essentially in the same manner as described in connection with the device shown in Fig. 1. The wires are first formed into an overtwisted strand by a twisting head such as shown at 20 in Fig. 1 and are then delivered to the capstans 45, 45 and flyer 53 which act as an untwisting head being independently rotated in the same direction but at a slower speed than the first twisting head. In this case the lineal speed of the strand through the whole device is determined by the rate at which the capstans 45, 45 are driven. These capstans in turn may be made to rotate at a speed having any given proportion to the speed of rotation of the frame 40 by appropriate changes in the gear ratios of the gears 49 and 50 or of the worm and worm gear 47, so that the number of twists per length of strand can thus be controlled.

5

Referring now to Fig. 5, a modified arrangement is shown which may be used to adapt the apparatus to the production of a wire rope or a more complicated strand. In this modification, a lay plate 60 supported by a suitable bracket 61 fixed to the frame 10 may be interposed between the capstans 13, 13 and the rotatable shaft 19 shown in Fig. 1. To assist in the proper formation of the strand or rope, a closing die 62 may be mounted in the entrance end of hollow shaft 19 to rotate therewith.

When the capstans are incorporated in the untwisting head as described above in connection with Fig. 4, a lay plate and closing die may also be interposed, if desired, between the hollow shaft 19 of the main twisting head and the sheave or die leading the wires or strands to this twisting head.

In the operation of this modification, a single wire, strand or fiber element 63 may be threaded through the central hole in the lay plate 60, and the desired number of wires or strands 64 may be threaded through the remaining holes in this plate. The elements, either wires or strands, may thus be held in the correct positions relative to each other as they are led to the die 62 to be closed into a strand or rope as the case may be. In this arrangement, the twisting of the wires or strands together takes place between the stationary lay plate 60 and the twisting head 20. Thereafter, however, the strand or rope is handled as described above, being overtwisted as it is formed and then untwisted the desired amount by the untwisting head that includes the flyer.

The terms and expressions which I have employed are used in a descriptive and not a limiting sense, and I have no intention of excluding such equivalents of the invention described, or of portions thereof, as fall within the purview of the claims.

I claim:

1. Apparatus for forming wire strand or rope which comprises means for supplying a plurality of wires or strands, a rotary twisting head for twisting said wires or strands together with an overtight as they are formed into a strand or rope, and separate twisting means separately driven to rotate in the same direction as said head but at a slower rate of speed, said twisting means being arranged to receive the rotating strand or rope directly from said head and thereby remove a controlled amount of twist from the overtight strand or rope.

2. Apparatus for forming wire strand or rope which comprises separate rotary twisting heads arranged in tandem, means for supplying to the first of said heads a plurality of wire elements to be twisted together, means for rotating said first head at a rate sufficient to overtight said elements, and separate means for rotating the second head in the same direction but at a slower rate of speed than said first head.

3. Apparatus for making wire strand or rope with a desired amount of rotational tendency which comprises a twisting means and a separate rotary device arranged in tandem to rotate about a common axis, means for rotating said twisting means and said device with the twisting means rotating faster than said device, means for supplying a plurality of separate elements to said twisting means to be twisted thereby into a rotating product, and spooling means cooperating with said device for collecting the product and simultaneously arresting its rotation.

6

4. Apparatus for producing wire strand or rope which comprises a pair of separate twisting members arranged in tandem for rotation about a common axis, means for supplying a plurality of wire elements to the first of said members without rotating said elements on their own axes, means for pulling said elements through said members as the wires are formed into a twisted product, and separate means for rotating said members at different speeds but in the same direction with the first of said members rotating at the higher speed.

5. Apparatus as defined in claim 4 in which the pulling means is driven at a speed proportional to the speed of one of the twisting members.

6. Apparatus for producing wire strand or rope which comprises a twisting head, means for rotating said head, means for feeding a plurality of wire elements to said head to be formed thereby into a rotating strand or rope, a separate flyer rotating at a slower speed to receive said strand or rope from the twisting head, a rotatably supported take-up spool to receive the strand or rope from the flyer, and a controllable brake on said spool to hold said strand or rope under tension from the time it is formed until it is collected on the spool, said flyer and spool being arranged to deliver the strand or rope onto the spool and simultaneously arrest its rotation.

7. Apparatus for producing wire strand or rope which comprises a pair of twisting heads arranged in tandem and rotated independently of each other about the same axis and in the same direction, means for rotating the first of said heads at a higher speed than the second of said heads, means for feeding to said heads a plurality of wire elements to be twisted together, a rotatably supported take-up spool, a flyer having an arm rotating about the spool to wrap the twisted product thereon, and a brake on said spool to maintain tension on the product as it is formed.

8. A method of producing wire strand which comprises twisting together a plurality of wires to form a strand that is overtight, and untwisting said overtight strand a predetermined amount to leave the strand with the desired amount of residual twist.

9. A method of producing wire strand or rope having a predetermined residual tendency to rotate which comprises feeding a plurality of separate wire elements in the direction of their length, twisting said elements together to produce a product that rotates on its axis and is overtight a predetermined amount as it is formed, and partially untwisting the rotating product to leave it with the amount of twist desired in the final product.

10. A method of producing wire strand or rope having a predetermined residual tendency to rotate which comprises feeding a plurality of separate wire elements in the direction of their length, twisting said elements together to produce a product that rotates on its axis and is overtight a predetermined amount as it is formed, reducing the speed of rotation of said product to remove the excess twist, and delivering the product onto a spool and simultaneously arresting its rotation without further changing its twist or length of lay.

11. A method as defined in claim 9 in which the speed of feeding the elements in the direction of their length is proportional to the speed of

rotation of the product after being partially untwisted.

12. A method of producing wire strand or rope having a predetermined amount of residual tendency to rotate which comprises twisting together a plurality of wire elements while said elements are advanced lengthwise at a given lineal speed to form an overtwisted product rotating on its own axis, reducing the speed of rotation of said product on its axis and thereby removing some of its twist while the advance of the product continues at the same speed, the speed of rotation of said overtwisted product bearing a predetermined ratio to said reduced speed of rotation of the product, collecting the strand or rope thus formed, and maintaining a controlled tension on said elements during both said twisting and partial untwisting.

13. Apparatus for producing wire strand or rope having a predetermined amount of residual twist which comprises a device for feeding a plurality of wire elements lengthwise at a given speed, a twisting head rotatable on the axis of the product for forming said elements into a strand or rope, a spool to receive the product, a flyer rotatable on said axis independently of said head and spool but arranged to receive the rotating strand or rope from said head and deliver it to said spool, driving means for rotating said flyer, means for driving said twisting head at a faster speed than said flyer, and a constant tension brake on said spool to maintain the strand

or rope between the spool and said feeding device under a substantial tension.

14. Apparatus for producing wire strand or rope which comprises a pair of twisting heads arranged in tandem and rotated independently of each other about the same axis and in the same direction, means for rotating the first of said heads at a higher speed than the second of said heads, means for feeding to the first of said heads a plurality of wire elements that do not rotate on their own axes, a rotatably supported spool, a brake for retarding rotation of the spool, and a flyer for receiving the rotating product, arresting its rotation and wrapping it on the spool.
